CROSS ROLLING MACHINE

George Breza, Pittsburgh, and Finn B. Abramsen,
Whitehall, Pa., assignors to The Mackintosh-
Hemphill Company, Incorporated, Pittsburgh,
Pa., a corporation of Delaware

Application April 14, 1950, Serial No. 155,938

7 Claims. (Cl. 153—91)

1

This invention relates to method of and apparatus for straightening and polishing tubes and round stock by the use of cross rolls to straighten the tube or rounds in a single pass through the rolls.

It is among the objects of the invention to provide a method of imposing bending stresses on rotating tubular or round stock to exceed the elastic limit of the material to straighten the stock in all planes without lowering its collapsibility resistance.

It is a further object of the invention to provide multiple cross roll passes for subjecting tubular or round stock to rotating and axial movement in which a pair of rolls of one of the passes is subjected to oscillations at a predetermined rate and thrust.

In the cross-roll straightening of round stock preferred practice is to engage the stock between two pairs of cooperative cross rolls which define a pass-line. Whereas these rolls are contoured and some straightening effect, particularly with respect to short bends, or kinks, is effected in each cooperative pair, the major straightening effect is performed by a deflecting roll, or pair of rolls, mounted intermediate the two cooperative pairs which define the pass line. The function of this deflecting roll, or rolls, is deflectingly to flex the stock held in the pass line and in cooperation with the pass-defining rolls to impose on it a permanent set of straightened condition. At least one of each of the two rolls of each pass-defining pair is driven positively. The single deflecting roll, or pair of deflecting rolls, can be idlers, although if desired such rolls can be driven positively. The round stock, such as a bar, tube or the like, rotates about its longitudinal axis as it progresses through the machine.

Because the working by the intermediate deflecting roll, or rolls, must be relatively severe in order to flex the stock beyond its elastic limit, the action results in a substantial work-hardening of the stock. While the work-hardening is for most purposes unobjectionable, or desirable, it should be avoided in connection with stock intended for certain prospective uses. This is true in the case of tubes in use of which subjection to extreme externally applied pressure is anticipated. In such case work-hardening decreases the resistance of the tube to collapse under such external pressure.

In accordance with this invention relief substantially decreasing work-hardening during straightening is provided by rendering the in-

2

termediate deflecting pressure on the stock rapidly intermittent, so that the rotating stock is deflected by a rapidly repetitive series of thrusts rather than by a uniformly applied deflecting force. In the apparatus embodiment of the invention, this is effected by relatively rapid oscillatory movement of the deflecting roll or rolls across or from the pass line.

Because work-hardening of the stock is objectionable only for certain prospective uses, it is desirable so to construct the machine that the oscillatory action on the stock can be omitted and the apparatus operated in a more usual manner for cross-roll straightening machines of the type to which it belongs.

It has been found desirable to equip cross-roll straightening machines of the general type under consideration with an unopposed deflecting roll positioned at each end of the apparatus. The function of such rolls is to remove bends near the ends of the stock by flexing the stock against the center provided by the gripping action of the adjacent pair of pass-defining rolls. I have found it advantageous that the action of such rolls consist of a timed deflecting thrust rather than that it be exerted as a continuous flexion caused by a set deflecting position of those rolls.

It is the object of our invention to provide a method of cross-roll straightening and apparatus therefor by which I obtain the advantages indicated above together with such further advantages as are inherent in the practice of the method or the structure of the apparatus.

These and other objects of the invention will become more apparent from a consideration of the accompanying drawings, constituting a part hereof, in which like reference characters designate like parts, and in which:

Fig. 1 is a front elevational view of a cross roll straightening machine embodying the principles of this invention;

Fig. 2 is a top plan view thereof;

Fig. 3 an end elevational view, partially in cross section, of the apparatus shown in Figs. 1 and 2;

Fig. 4 a vertical section, partially in elevation, of an adjusting mechanism for adjusting the upper and lower center cross rolls to thereby adjust the roll pass;

Fig. 5 a cross sectional view, partially in elevation, taken along the line 5—5, Fig. 2, of the roll oscillating mechanism and a portion of the machine canopy;

Fig. 6 a vertical cross sectional view, partially in elevation, of a portion of the oscillating

mechanism of Fig. 5, the section being taken on line VI—VI of Figure 2;

Fig. 7 a cross sectional view, partially in elevation, taken along the line 7—7, Fig. 5;

Fig. 8 a cross sectional view, partially in elevation, of the roll adjusting mechanism.

With reference to the several figures of the drawings, numeral 1 designates a base plate of a cross roll mill having a canopy 2 and columns 3, 4, 5, 6 and 7 secured to the base and canopy by nuts 8 interacting with screw threaded ends 9 of the columns. Mounted on the base are a plurality of journal housings 10 and 11 for cross rolls 12 and 13, respectively. Movable mounted in the base 1 are roll housings 14, 15 and 16 for supporting cross rolls 17, 18 and 19, rolls 17 and 19 being the end rolls, sometimes referred to as gag rolls, and the center roll 18 being one of a pair of oscillating rolls. All of the rolls are angularly adjustable by hand wheels 20 and 20a, and the end rolls 17 and 19 are vertically adjustable by apparatus consisting of the links 21 attached to the journal housings 14 and 16 at the bottom and to cross frames 22 at the top.

As shown in Fig. 3, the cross frames are vertically slidable on a reduced cylindrical portion 23 of the columns 3 and 7 and are provided with bearing bushings 24 that have sliding contact with the cylindrical portions 23. The roll housings 14 and 16 are slidably mounted on columns 3 and 7 by bearing bushings 25. The cross frame 22 is subjected to vertical movement by a plurality of eccentrics 26 disposed in sliding bearing blocks 27 which are permitted to slide horizontally in a horizontal opening in the cross frame 22. The eccentrics 26 carry segment gears 28, Figs. 1 and 2, that are actuated by a rack 29 connected to a suitable prime mover such as a piston rod 30 of a cylinder 31 that may be hydraulically or pneumatically operated. When the rack 29 is actuated through cylinder 31, the eccentrics 26, Fig. 3, will be turned to raise or lower the bottom rolls 17 and 19 for a purpose hereinafter explained.

Mounted on columns 4, 5 and 6 are a plurality of upper roll housings 32, 33 and 34 which carry cross rolls 35, 36 and 37, respectively, which, together with the bottom rolls 12, 13 and 18, form cross roll passes which may be designated by the reference characters A, B and C, as indicated.

The roll housings 32, 33 and 34 are vertically adjustable on their respective columns 4, 5 and 6 by mechanism shown in Fig. 4. The numeral 33 designates the housing for roll 36 which is the center top roll, and the adjusting mechanism for the housings 32 and 34 is as shown in Fig. 4, except there are no connecting links like the links 38 in Fig. 4, which are employed on the center housing only to connect the lower roll housing 15 with an oscillating frame 39, as shown in Fig. 1. Since there is no adjustment of the lower rolls 12 and 13 of the passes A and C, there is no threaded sleeve on the columns 4 and 6, but the columns themselves are threaded.

The upper roll housings 32, 33 and 34 are adjustable vertically by nut members 40 and 41 which are grooved to receive the housings 32, 33 and 34 as shown in Fig. 4. Each of the nuts 40 and 41 is provided with worm teeth or threads 42 and 43 that interact with worms 44 and 45, respectively. There is a set of housing adjusting nuts like the nuts 40 and 41 on the front and rear columns and there are two worms on each

of the worm shafts 46 and 47 which terminate in gear boxes generally designated by the numeral 48, Fig. 1. The worm shafts 46 and 47 are geared together by gear wheels 49 and 50, the gear 49 being keyed to shaft 46, as shown at 49a, and gear wheel 50 being journaled on a bushing 51, Fig. 9. A locking pin 52, mounted in a crank arm 53 that is keyed at 54 to the shaft 47 locks the gear wheel 50 with the shaft 47, and in locked position shafts 46 and 47 rotate simultaneously through the gear wheels. Shaft 46 is provided with a square end 55 by which it can be rotated by a wrench. Shafts 46 and 47 may be simultaneously driven by motors 56 shown in Figs. 2 and 3, there being a separate motor for each set of upper roll housing adjusting nuts.

As shown in Fig. 4, a cover 57 in the form of a tube is secured to the nut 41 to act as a protector for the threaded portion 58 of a sleeve 59 that is keyed against rotation on the column 5. A sleeve 60 is slidably mounted on column 5 and is adjustable vertically by a ring nut 61. When the end of the sleeve 60 abuts the lower end of threaded sleeve 59 the latter is displaced vertically until it abuts the surface 62 of the canopy 2 and is held against sliding movement on columns 5 by engagement between the canopy and the sleeve which locks the roll housing 33. When this adjustment is made, the screw nuts 63, 64, 65 and 66 on the connecting links 38 are loosened, disconnecting the oscillating mechanism.

The housing 33 and its roll adjusting mechanism is oscillated by the cross frame 39 by means of an eccentric drive shown in Figs. 1, 2, 5, 6, 7 and 8. It consists of a motor 67 driving a shaft 68 through a speed reduction mechanism 69 that is mounted on an extension 70 of the canopy 2. The oscillating frame 39 is adapted for sliding movement vertically by vertical slides on the bearing brackets 72, Fig. 6. Shaft 68 is journaled in roller bearings 71 disposed in the bearing brackets 72 bolted to the canopy 2 by bolts 73, Fig. 6, and the oscillating frame 39 is suspended from shaft 68 by roller bearings 74 in which is disposed an eccentric sleeve 75 which, as shown in Fig. 7, is journaled on an eccentric 76 of shaft 68. There are two eccentric sleeves 75, one at each end of the shaft 68, and they are provided with clutch faces as shown at 75a, Fig. 5, which interact with complementary shaped faces of a housing 77. Mounted in the housing 77 is a worm 78, the threads 79 of which interact with worm gear teeth 80 provided in shaft 68. By turning the worm 78, the housing 77 and its interconnected sleeve 75 will be displaced angularly relative to the shaft 68, so that the eccentric sleeve 75 will be angularly displaced relative to the eccentric 76 of shaft 68, thereby varying the thrust or magnitude of oscillations of the interconnected upper and lower center roll housings 33 and 45, respectively. In the view shown in Fig. 7, for example, the eccentric 76 is disposed in the same direction as the eccentric sleeve 75, which produces maximum thrust on the oscillating rolls. By rotating the adjusting worm screw 78 a range of adjustment through 180° can be made, so that when the eccentrics 76 and 75 are oppositely disposed to the position shown in Fig. 7, a minimum thrust of the oscillating mechanism is obtained.

When it is desired to operate the apparatus without oscillating the rolls 18 and 36 of pass B, the roll-carrying assembly of the pass is locked in the manner described above. Prior to such

locking, eccentric sleeves 75 are adjusted to raise the roll-carrying frame enough to place the face of roll 18 in the desired position with respect to the pass-line and shaft 68 is operated to effect that adjustment. This defines a set deflecting position of roll 18. After the locking action roll 18 can act alone or roll 36 can be lowered into cooperative position by nuts 40 and 41 also to contact the stock in this deflecting region. Adjustment of the bottom roll 18 may also be effected by adjusting the bottom nuts on links 38 to raise or lower the bottom roll housing 15.

The top and bottom cross rolls of the end passes A and C are motor driven through shafts 81, 82 and 83, 84, Fig. 2 of the drawings, the shafts 81 and 82 being connected with the drive shafts of the upper rolls 35 and 37, and shafts 83 and 84 with the bottom rolls 12 and 13, each pair of shafts 81 and 82 and 83 and 84, respectively, being operated through a gear box from a common motor, not shown, so that the rolls of the roll passes A and C are driven at equal speeds. The speeds may be adjustable to vary the effect of one or both of the driven passes on the stock, if desired, such adjusting mechanism being no part of the present invention.

Disposed in the line of travel of the tubular or round stock through the roll passes are electric eyes 85 and 86 connected to solenoid valves which control the operation of the cylinders 31, whereby when the end of the tube or round passing through the straightening machine reaches or intercepts the beam of the electric eye 86, the cylinder 31 will be energized to raise the roll 19, and when the rear end of the same piece of tubing or round stock reaches the electric eye 85, it will control the cylinder 31a to raise the roll 17 for a purpose to be hereinafter stated.

The above described apparatus functions briefly as follows.

The tubing to be straightened is entered in the roll pass A from which it is driven through the roll pass E, which is not a driven roll pass, and again driven when it enters the roll pass C. Since the same motor drives the bottom rolls of passes A and C, both sets of rolls of passes A and C will be driven at the same speeds. As the tubing passes through the straightening machine, the rolls of the driving passes A and C rotate the tubing continuously while feeding it forward in the direction from A to C.

The roll passes A, B and C are previously adjusted by adjusting the angle of the rolls through the hand wheels 20 and the wheels 20a, and they are vertically adjusted to size of stock by energizing the motors 56 which adjust the upper rolls. The center roll pass B, which is the oscillating pair of rolls, is similarly adjusted to size of the tubing and the thrust or magnitude of oscillatory motion of the oscillating frame 39 is set by the adjusting worm 78, Figs. 5 and 6. The throw of the oscillator is set for different size of pipe to a degree sufficient to bend the metal to exceed the elastic limit. The oscillatory motion of these off-setting rolls reduces work hardening stresses. The thrust of the oscillating rolls is adjustable not only for the different size of the tubing, the larger the pipe or tube the less deflection necessary, but also in accordance with the physical property of the metal. By the continuous rotation of the tubing while passing through the oscillating rolls, the tube is straightened in all planes. In the center pass B, which is the pass of the oscillating rolls, the adjusting screws for the rolls operate together. Dur-

ing operation the pin 52, Figs. 1 and 9, locks the gear wheel 50 to the shaft 47. When adjustment is made of the upper roll 36, the pin 52 is removed from the gear 50 so that the lower nut

5 40 can be backed off from housing 33 by rotation of the worm 45. Pin 52 is then locked in the opening of the gear designated by numeral 52a and both worms 44 and 45 rotate to raise or lower the housing a distance to suit the diameter of the tubing. The pin 52 is withdrawn from 52a and lower nut 41 is raised by rotation of worm 45 to clamp housing 33 against upper nut 40. The link nuts 63 to 66 are loosened when this adjustment is made.

10 15 As the front end of the tube passes from the roll pass C into the beam of the electric eye 86, the actuator 31 will cause the roll 19 to be raised to deflect the end of the tube to straighten it; and when the rear end of the tube passes the electric eye 85, actuator 31a will raise the end roll 17 to deflect the tail of the tube.

It is evident from the foregoing description of the invention that the method and apparatus for straightening tubes or rounds therein dis-

25 closed will straighten the stock at great speed and without detrimentally work hardening the metal. Any appreciable degree of work hardening, such as results from conventional cross roll tube straightening methods, would diminish resistance to collapse from external pressures in use. The oscillatory movement of the center rolls is approximately 300 oscillations per minute, and the speed of travel of the stock through the passes is 75 to 300 feet per minute. The thrust 30 35 adjustment of the oscillating mechanism is approximately from 0" to 1" maximum by means of the relative angular positions of the eccentric sleeve 75 to the eccentric 76 of shaft 68.

Although one embodiment of the invention 40 has been herein illustrated and described, it will be evident to those skilled in the art that various modifications may be made in the details of construction without departing from the principles herein set forth.

45 We claim:

1. Apparatus for straightening tubular or round stock comprising a plurality of cross roll passes, some of the pairs of rolls being driven to rotate and feed the stock through the passes, 50 one pair of said cross rolls being mounted in an oscillating frame and offset from the driven rolls to impose bending stresses on the stock material beyond the elastic limit, means for actuating said frame to subject said pair of offset rolls to oscillatory movement to prevent work hardening of the stock material, bottom rolls constituting end rolls for supporting the stock before and after it enters the multiple roll passes, and means for raising said end rolls to deflect the ends of 55 60 the tubular or round stock while passing through the multiple straightening rolls.

2. Apparatus for straightening tubular or round stock comprising a plurality of pairs of cross rolls constituting multiple roll passes, the 65 end pairs of rolls of which are driven and an intermediate pair of rolls of which are idle rolls, and means for subjecting the idle rolls to oscillatory movement while the stock is passing therethrough, said means consisting of a cross frame supporting the top and bottom idle rolls and an eccentric drive for subjecting the cross frame to reciprocatory movement in a vertical plane.

70 75 3. In a cross roll mill for rolling tubular or round stock, an upper and lower roll constituting a roll pass, means for adjusting the upper roll

vertically to the lower roll consisting of a plurality of supporting columns for supporting the upper roll housing at the respective ends thereof, said columns having threaded portions, threaded nuts coacting with the threads of said columns, each of said nuts having worm screw threads, worm screws interacting with the worm screw threads of said nuts, and means for actuating said worm screws independently or simultaneously to adjust the relative vertical position of the upper roll housing, said nuts having body milled portions and said housing having bores interacting with the body milled portions of the nuts, said body milled portions having shoulders for engaging shoulders of the roll housing.

4. Cross roll mechanism as set forth in the next preceding claim in which the worm screw actuating means comprises a plurality of worm shafts with their axes in parallel relation, one of said shafts having a bushing, a gear journaled for rotation on said bushing, a crank arm keyed to the end of the shaft, a locking pin mounted on said crank arm, said gear having a recess for receiving the end of the locking pin whereby the gear is interlocked with said shaft, and the other of said shafts having a gear wheel keyed thereon, the teeth of which interact with the teeth of the first-named gear wheel.

5. In a cross roll mill for rolling tubular or round stock, a pair of rolls constituting a roll pass, a separate housing for each of said rolls, supporting columns for said housings, a threaded sleeve on each of said columns splined on said columns for axial movement thereon, a threaded portion at the bottom of the columns, a ring nut on said threaded portion and a sleeve slidingly mounted on the column abutting one face of the ring nut at one end and in register with the end of the threaded sleeve at its other end, a plurality of screw nuts mounted on the threaded sleeves of the columns having their threads interacting with the threads of said sleeve, said nuts having radial flanges constituting shoulder abutments for one of the roll housings, links connecting the last-named roll housing with the other roll housing, and locking means for interlocking one of said roll housings with said links, said nuts having worm gear teeth and screw worms journaled in the housing abutting the shoulders of said nuts in threaded engagement with the worm gear teeth of said nuts, and means for

actuating said worm gears to rotate said nuts on the threaded sleeve severally or simultaneously.

6. In a cross roll mill for tubular or round stock, a pair of cooperating rolls, each journaled for rotation in a roll housing, supporting columns for said roll housings, an oscillating frame, links connecting said frame with said roll housings, actuating mechanism for subjecting said frame to oscillatory movement to thereby oscillate the roll housings and their respective rolls, said mechanism consisting of a shaft journaled independently of said oscillating frame having an eccentric body portion, an eccentric sleeve mounted on the eccentric portion of the shaft and journaled in said oscillating frame, and means for adjusting the relative angular position of said eccentric shaft portion and sleeve to thereby vary the thrust of said oscillating frame.

7. In a cross roll mill for tubular or round stock having cooperating rolls constituting multiple roll passes and having gag rolls at the respective ends of said multiple roll passes, said gag rolls being mounted in roll journals, a cross frame for supporting said roll housings, links connecting said cross frames to said roll housings and means for raising said top frame, said means comprising an eccentric engaging a surface of the cross frame to raise and lower the same, and means for actuating said eccentric comprising a gear and rack mechanism and means for actuating said rack mechanism.
